(57) **CLAIM**

The ornamental design for shoe, as shown and described.

DESCRIPTION

3. Shoe sole

3.1: Perspective view of a shoe

3.2: front view thereof;

3.3: back view thereof;

3.4: side view thereof;

3.5: Opposite side view thereof;

3.6: top view thereof; and

3.7. bottom view thereof.

The shoe has a sole and an upper with a lace-up vamp; the upper has an opening for the introduction of a foot, which is surrounded by a padded edge; the sole which on its lateral perimeter has a succession of hexagonal channel openings, has three lateral vertical grooves defining four segments; the shoe in the images is a left shoe and is intended for use with a symmetrical right shoe; dashed lines in the images represent characteristics that are not part of the design and are not claimed.
